METHOD AND APPARATUS FOR PRESERVING STERILE SUTURE MATERIAL FOR MEDICINAL PURPOSES READY FOR USE

Ernst Gelinsky, Berlin, Germany

Application September 26, 1934, Serial No. 745,637
In Germany October 16, 1933

7 Claims. (Cl. 128—335.5)

This invention comprises an improved method and apparatus for preserving sterile suture material for medicinal purposes ready for use.

Suture material for medicinal purposes made sterile ready for use is stored either dry or moist. When stored in the dry state, it is usually wrapped in paper and supplied to the consumer enclosed in cardboard boxes. The thread remains sterile until it is used, but on account of its dryness, particularly in the case of catgut, it has the disadvantage that it is brittle, and knots made with it do not hold well. For this reason the catgut thread is employed for example in clinics, usually in the moist condition, by placing it in alcohol or other liquids which are sterilized with difficulty or are maintained germ-free by added disinfectants. The storing of the suture material is effected in glass troughs and the like, and necessitates considerable care and trouble, although in regard to the sterility the result is not always commensurate with the trouble taken. Such suture material which is prepared moist in large quantities ready for use, can only be transported under very great difficulty. In addition, in view of the fact that the vessels are left open during use, it is doubtful whether the thread is maintained sterile.

The present invention eliminates the defects and disadvantages enumerated in the foregoing, and for the first time permits the use of sterile suture material which is always ready for use anywhere and at any time down to the last remaining portion.

According to this invention suture material is preserved in a sterile manner even during use by embedding the same in a sterile or disinfectant plastic mass, which may be either a semi-soft (even without heating) unctuous mass consisting of known mixtures e. g. wax, paraffin, petroleum jelly, tragacanth, etc., or by embedding the suture material in sterile or disinfectant liquids (benzine, alcohol and the like) or in solutions of disinfectants e. g. which are rendered plastic. This latter method may be carried out by causing to be formed high molecular organic acid salts such as resinic acid salts or fatty acid salts or salts from inorganic tetrachlorides, etc., in these liquids or solutions, the result being the formation of a plastic mass suitable for use in carrying out my present invention, as will be described.

50 The plastic mass thus formed has the physical properties of a solid and the bacteriological properties of a liquid.

Containers of glass, hard and soft metals and other materials in any form are suitable for containing the sewing material which is surrounded

by the plastic mass in which the suture material is embedded for storage until use.

The methods which have been described are suitable for absorbable surgical suture material and are also useful for the preservation of non-absorbable suture material.

A method of packing is shown more particularly in its details in the accompanying drawing, but the application is not restricted to this method.

Referring to the drawing, in a vessel A is a roller B on which the catgut thread C is wound. D are various knots in the thread which are necessary because such thread can be of a limited length only. The vessel A which may be made of glass or any other suitable material, such as sheet metal, artificial or synthetic substances or the like is closed on the underside by the bottom E, which is sealed at F by seaming, screwing or the like, if desired with the interposition of a packing, after the roller B has been inserted into the vessel. In the vessel which for example may be made rather flat in shape, there may be provided lateral abutments G against which the projecting ends of the roller B can abut during the pulling off of the catgut thread C, in order thereby to avoid displacement and jamming of the roller B in the vessel A. Likewise it is possible for the thread to be wound in a previously sterilized bottle, if desired round a glass rod mounted in bearings suitably disposed in the glass vessel, the said rod being rotatable about its longitudinal axis. The vessel A is filled with a sterile plastic mass H in which the suture material is embedded and from which it may be readily withdrawn for immediate use.

As an example of one specific disinfectant that may be used we give the following, which is made up of two solutions:

Solution A: 2.0 cc. acid carbol. in 98.0 cc. of 96 per cent alcohol; and

Solution B: 10.0 grams of acid palmitic dissolved with the application of heat in 100.0 cc. of 84 per cent alcohol, saponified to neutral reaction with a corresponding quantity (about 14.0 cc.) of a 10 per cent solution of caustic soda.

Equal parts by volume of these two solutions are mixed with the application of heat. The catgut is embedded in the still fluid mixture, which upon cooling solidifies into a plastic mass. Suitably provided in the neck of the vessel A and/or in a closure member K are wiping devices J, which may for example comprise wires or the like extending towards each other in a conical formation, and wiping the thread C during its withdrawal, such that the adherent filling material H is wiped off as far as possible. In the said closure

member are membranes for example L, L', L'', made of resilient material provided in the centre with a fine opening through which the thread C and if necessary also the knots D are drawn, the 5 membrane openings bearing perfectly tightly, resiliently and firmly on all sides against the thread C. For example, the two diaphragms L, L' may be made of rubber perforated or incised for the passage of the suture. There may also be 10 placed between the membranes an absorbent layer M, for example of kieselguhr or some other absorbent material. In addition to providing a further meticulous wiping, this arrangement also prevents the thread from slipping back. When 15 not in use, the vessel A is firmly closed by a well-fitting cover T.

In order to be able to handle the commercial packing in a manner which ensures sterility to a degree comparable with the handling of metal 20 instruments, which can be boiled, a two part metal case N which can be made sterile by boiling is provided, and the vessel A is enclosed in the said case. The thread is then drawn through a hole O in the lid P. In some cases, in the absence of 25 other wiping devices, a resilient clamp for a tampon or swab may be provided above the said lid, a freshly sterilized tampon being inserted in the said clamp on each occasion. The thread is then drawn through the said tampon. The as- 30 sistant may also hold the tampon in front of the opening for the thread, all wiping devices being thereby eliminated and the threads may be wiped in this manner, since the sterility of the vessel permits this. Such a vessel N with lid P can be 35 carried about at any time and everywhere, so that sewing is always carried out in a reliably sterile manner.

By the use of the invention which has been described, all of the advantages of a solid em- 40 bedding material for the sterilized mass of suture material to be stored or preserved until ready for use, are attained. Thus, the air-tight sealing of the containing vessel to prevent evaporation, necessary in a liquid antiseptic into which the 45 suture is immersed, is unnecessary; the holder if accidentally overturned does not lose the sterile body or mass in which the suture is embedded, and yet, because of its plastic nature, the thread

of suture material may be drawn out at any time and to any extent and the spool or other carrying support for the embedded mass of suture material may be turned as becomes necessary when the suture is withdrawn.

I claim:—

1. A method of preserving suture material for medicinal purposes in a sterile state before and during use by storing the same in high molecular organic acid salts in solution which when cool 1 solidify into a plastic mass.

2. A method for preserving suture material for medicinal purposes in a sterile manner before and during use, by storing the same in sterilized resinic acid solutions which are solidified by the 1 addition of a base into a plastic mass.

3. A method of preserving suture material for medicinal purposes in a sterile manner before and during use by storing the same in sterilized higher fatty acid solutions which are solidified by the 2 addition of a base into a plastic mass.

4. A method of preserving absorbable suture material for medicinal purposes in a sterile manner before and during use by storing the same in sterile higher fatty acid solutions which are solid- 2 ified by the addition of a base into a plastic mass.

5. A method of preserving non-absorbable suture material for medicinal purposes in a sterile manner before and during use by storing the same in sterilized higher fatty acid solutions which are 3 solidified by the addition of a base into a plastic mass.

6. A method of preserving suture material for medicinal purposes in a sterile manner before and during use by storing the same in liquids which 35 have been made disinfectant by the addition of disinfectants and which are solidified into a plastic mass by the addition of resinic acid and a base.

7. A method of preserving suture material for 40 medicinal purposes in a sterile manner before and during use by storing the same in liquids which have been made disinfectant by the addition of disinfectants and which are solidified into a plastic mass by the addition of fatty acid and a 45 base.

ERNST GELINSKY.
